UNITED STATES PATENT OFFICE.

JAMES P. PERRY, OF GLENCOE, NEW MEXICO.

BOILER.

1,350,565.

Specification of Letters Patent. Patented Aug. 24, 1920.

Application filed August 2, 1919. Serial No. 314,821.

To all whom it may concern:

Be it known that I, JAMES P. PERRY, a citizen of the United States, and a resident of Glencoe, county of Lincoln, and State of New Mexico, have invented a new and Improved Boiler, of which the following is a full, clear, and exact description.

This invention relates to steam plants or boilers.

10 An object of the invention is to provide a steam boiler design which will have a great deal of heating surface and which will be comparatively small in size, in order to provide a suitable boiler for use on aeroplanes, automobiles and other vehicles; and which will also find a use in any capacity where it is necessary to produce steam for operation of steam engines and turbines.

20 An object of the invention is to provide a boiler which will gain full advantage of heat derived from combustion of fuel. The boiler is simple in construction, accessible to repair and dependable in steam generating capacity.

25 Another object is to provide a boiler which has an outer jacket construction which may be quickly assembled and removed from the boiler shell in order to clean the boiler parts.

With the above principal objects, and 30 others, in view, the invention has relation to an arrangement of boiler parts and elements, an example of which is described in the following specification, pointed out in the appended claims and illustrated in the 35 accompanying drawings, wherein:

Figure 1 shows a vertical section of the boiler, and Fig. 2 shows a horizontal section as would be taken upon the line 2—2 of Fig. 1.

40 Fig. 3 is a longitudinal sectional view of one of the plurality of water tubes shown inserted in the boiler shells.

Fig. 4 is a side elevation of the boiler, and Fig. 5 is a plan view thereof.

45 In constructing a boiler according to the plans of my invention, I employ an inner and outer boiler shell which provides an annular water space. A plurality of heating tubes are inserted through the water space and expose the water to heat circulated through the boiler. Other novel features of the construction therewith will appear as the description is continued.

Referring now more in particular to the 55 drawings, the reference numerals 6 and 7 point out an inner and outer boiler shell.

The inner shell is closed by heads 8 and the outer shell is closed by heads 9. The boiler shells are spaced in concentric relation by upper and lower rings 10 which are provided with holes formed therein to permit circulation of water. In this manner a concentric water space is formed between the inner and outer boiler shells.

50 A water reservoir is disposed centrally through the boiler shells. This comprises a water column or tube 11 fitted into the upper set of heads 8 and 9 and closed by a cap 12 at the upper end thereof, and closed by a plug 13 at the lower end thereof. The upper portion of the water reservoir is provided with steam take-off pipes 14, and the upper portion of the water reservoir 11 may be termed a steam dome employed to collect steam generated within the water space of the boiler. The steam dome or upper end of the reservoir 11 is apertured as shown at 15 to permit steam to pass from the water reservoir to the pipes 14. Apertures 16 are also provided below the water line in order to 60 permit circulation of water through the reservoir 11 and boiler.

65 A perforated pipe 17 is inserted through the upper set of heads 8 and 9 of the boiler shells and provided on the upper end thereof with a safety valve 18. The lower end of the perforated tubes is fitted with a fusible plug 19 which will melt should the boiler become dry and direct a stream of steam or water downwardly through the boiler to 70 quench the fire and permit the boiler to cool off to prevent damage. This perforated tube 17 is shown in Fig. 1, and it will be understood that any type of safety valve 18 will be employed.

75 A plurality of water tubes 22 is carried by the concentric boiler shells approximately right-angular with the axis of the boiler and disposed radially. These boiler tubes will be constructed and assembled with the 80 two boiler shells as shown in Fig. 3. The boiler tubes are provided with water circulation holes 23 to admit water from the annular water chamber into the tubes. The tubes terminate inwardly adjacent the water 85 reservoir 11, and extend outwardly from the outer boiler shell. The radial arrangement of the boiler tubes is shown in Fig. 2, and Fig. 1 shows the tubes arranged in vertical tiers which permits a great number of these 90 water tubes to be inclosed within a small space.

A boiler jacket is provided around the system of radial water tubes and comprises a number of jacket sections 24. The jacket sections when assembled form a cylindrical boiler jacket. Each section is provided with a hinge bracket 25. A binder rod 26 is passed through the hinge bracket to hold the jacket sections together. A jacket head 27 is fitted upon the upper portion of the boiler, 10 and a base 28 is provided at the bottom thereof. The jacket head and base have attached thereto rings 29 which hold the sectional jacket in place. The retaining rods 26 are passed through the jacket head and 15 the base and secured thereto by nuts or other appropriate means. The retaining rods 26 function to hold the jacket sections together and secure the base and jacket head in spaced relation to form a unitary structure. The 20 outer concentric space left between the boiler jacket and the outer boiler shell provides an outer heating space. The outer ends of the radial water tubes therefore are mounted within this outer heating space. The interior of the inner boiler shell provides an 25 interior heating space or fire box. The inner ends of the water tubes are confined in the fire box.

A number of flue tubes 30 are fitted in the 30 boiler shells at the upper portion thereof in order to communicate the fire box with the outer heating space. A ventilator tube 31 is fixed in the base open at the lower end and normally closed at the upper end with 35 a plug 32. This plug 32 is held in place by a bolt 33. The plug 32 may be removed for inspecting the fire box and interior parts of the boiler. A heat outlet conduit 34 is provided underneath the boiler base and 40 communicates with the ventilator tube 31. The ventilator tube is apertured as shown at 35 in order to convey the heat from the outer heating space through the ventilator tube and into the heat outlet conduit 34. The 45 heat outlet 34 may be of any appropriate length in order to convey smoke and used heat away from the boiler. A damper valve 36 is controlled by a hand rod 37. The valve may be regulated in open or closed position 50 to cause a fast or slow movement of heat through the fire box into the outer heating space and from the boiler. It may be desirable to employ a thermostatic of approved design to control the opening and closing of 55 the damper valve 36.

A number of blow-out, or clean-out pipes 37^a are fitted through the boiler jacket into the water chamber. These blow-out pipes 37^a are provided with a closure valve, not 60 shown, which will be kept closed until such times as become necessary to open up the valves to clean the boiler of scale and sediment.

A number of water feed pipes 39 are 65 inserted through the boiler construction and

connect with the water reservoir 11. Water is fed through the pipes 39 to supply the boiler. A number of fuel tubes 40 are fitted in the boiler with the inner end thereof reduced in size to form flame nozzles. The 70 water feed and fuel feed pipes may be inserted through water tubes if desirable.

The flame issues from the fuel pipes 40 and is spread by the plug 13. The flame and heat passes upwardly through the fire box 75 around and through the plurality of water tubes and through the flues 30 into the outer heating space. The products of combustion are drawn from the outer heating space through the perforations 35 of the ventilator 80 tube 31 and outwardly through the conduit 34. This boiler provides a maximum amount of exposed heating surface, and comparatively small in size. This boiler may be adapted to a great variety of purposes where small and compact boilers are necessarily employed for particular uses.

Having thus described my invention, what I claim as new, and desire to secure by Letters Patent is:

1. A steam boiler comprising; an inner boiler shell forming a fire box, an outer boiler shell forming an annular water space, a boiler jacket forming an outer heating space, water tubes inserted through the annular water space and projecting into the fire box and into the heating space, flues inserted through the boiler shells to conduct heat from the fire box to the outer heating space, a central water reservoir disposed through the fire box, and a ventilator tube centrally disposed in the boiler and provided with perforations, a removable plug mounted in the ventilator tube to render accessible the boiler parts for inspection. 95 100 105

2. A steam boiler comprising; an inner boiler shell forming a fire box, an outer boiler shell forming an annular water space, a boiler jacket forming an outer heating space, water tubes inserted through the annular water space and projecting into the fire box and into the heating space, flues inserted through the boiler shells to conduct heat from the fire box to the outer heating space, a central water reservoir disposed through the fire box, a ventilator tube centrally disposed in the boiler and provided with perforations, a removable plug mounted in the ventilator tube to render accessible the boiler parts for inspection, and a heat 110 115 120 125 conducting outlet conduit connecting with the ventilator tube.

3. A steam boiler comprising; an inner boiler shell forming a fire box, an outer boiler shell forming an annular water space, a boiler jacket forming an outer heating space, water tubes inserted through the annular water space and projecting into the fire box and into the heating space, flues inserted through the boiler shells to conduct 130

heat from the fire box to the outer heating space, a central water reservoir disposed through the fire box, a ventilator tube centrally disposed in the boiler and provided with perforations, a removable plug mounted in the ventilator tube to render accessible the boiler parts for inspection, a heat conducting outlet conduit connecting with the ventilator tube, and a damper control mounted in the heat outlet conduit.

4. A steam boiler comprising; an inner boiler shell comprising a fire box, an outer boiler shell concentrically arranged with the

inner boiler shell to form an annular water space between the boiler shells, a plurality 15 of water tubes radially disposed through the concentric boiler shells with the inner end of the water tubes positioned within the fire box, a boiler jacket concentrically arranged with the aforesaid boiler shells to form an 20 outer heating space into which the outer end of the radial water tubes project, a central water reservoir, a water feed pipe, a fuel feed pipe, and a ventilating means.

JAMES P. PERRY.
